Nelson M. Leonard

UNITED STATES PATENT OFFICE.

ARTHUR F. PYM, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

Original application filed March 10, 1924, Serial No. 698,099. Divided and this application filed January 23, 1926. Serial No. 83,372.

This invention relates to lasting machines, and more particularly to shoe-end-lasting mechanism, this application being a division of my co-pending application for Letters 5 Patent for improvements in the manufacture of shoes, Serial No. 698,099, filed on March 10, 1924. The invention is herein illustrated in its application to the lasting of the toe ends of shoes, but it will be recognized that it 10 is not thus limited in its applicability.

An important object of the present invention is to provide improvements in mechanism for operating end-lasting wipers, i. e., for moving the wipers bodily lengthwise of a 15 shoe and for swinging them toward or from each other laterally of the shoe. The construction herein shown comprises a simple and convenient arrangement of wiper-operating mechanism, including a hand lever and 20 separate connections between the lever and the wipers for imparting to the wipers the different respective movements. Among other advantages, this facilitates the provision of means for adjusting the wipers toward or from each other to adapt them to operate upon shoes of different widths, and the invention further provides novel means for thus adjusting the wipers comprising, as 25 herein illustrated, mechanism whereby one 30 of the above-mentioned wiper-operating connections may be moved independently of the other to adjust the wipers for different widths.

A further feature of the invention consists 35 in novel means for effecting a relative variation between the extent of the bodily advancing movement of the wipers lengthwise of the shoe and the extent of their closing or swinging movement laterally of the shoe, to adapt 40 them to operate with the best results upon shoes of different shapes. In lasting the toes of welt shoes, for example, it is desirable that the wipers wipe the upper inwardly from the edge of the insole the same distance both at the end and at the sides of the toe. In order 45 to produce the most accurate results in this respect, the extent of the angular swinging movement of the wipers, for a given extent of

advancing movement, should be varied in accordance with how closely the sides of the toe 50 approach a parallel relation to the longitudinal median line of the forepart of the shoe. The invention provides convenient and effective means for accomplishing the desired result by varying relatively the rates of the 55 advancing and the closing movements of the wipers, the construction shown comprising a lever which is connected to the wiper-operating hand lever and is adjustable in length to vary the rate of the wiper-advancing movement relatively to that of the closing movement. 60

The above and other features of the invention, including various novel details of construction and combinations of parts, will 65 now be more particularly described by reference to the accompanying drawings and pointed out in the claims.

In the drawings,

Fig. 1 is a plan view of a toe-lasting machine in which the invention is embodied;

Fig. 2 is a section on the line II—II of Fig. 1; and

Fig. 3 is a view in front elevation on a smaller scale of a portion of the wiper-operating mechanism shown in Fig. 1. 75

For positioning, i. e. locating or supporting, the last and its shoe materials for the operation of the toe-lasting mechanism, any suitable means may be utilized, the construction herein shown comprising an arm 2 which is fast on the frame of the machine and is provided with a pin 4 adapted to enter a hole formed in the bottom of the last L, as more fully shown and described in the co-pending application of which this application is a division. It will be understood that the last and its shoe materials are thus held by the pin 4 against pressure of the lasting means thereon in directions lengthwise and laterally of the shoe. The arm 2 serves as a hold-down member, and the shoe is further supported underneath and pressed upwardly against this hold-down member by means of a toe rest not herein shown. 80 85 90 95

Pivots mounted at 6 on the frame of the

machine are a pair of arms 8 which are formed as extensions of a wiper head 10. The wiper head 10 supports toe-embracing wipers 12, as will be more particularly explained. As more fully shown and described in the co-pending application, the wiper head 10 is connected to a treadle whereby it may be swung upwardly about its pivots 6 to cause the wipers to wipe the upper heightwise of the toe and may also be swung downwardly to increase the pressure of the wipers on the upper after the upper has been wiped inwardly over the bottom of the last.

The wipers 12 are detachably secured to wiper holders 22 which are mounted on an extension 24 of a sleeve or carrier 26 (Fig. 2), which may also be termed a wiper carriage, guided for lengthwise movement in the head 10. The extension 24 is provided with an accurate guideway, and the wiper holders 22 have co-operating guide ribs 28, so arranged that the wipers have swinging or closing movements laterally of the shoe about a center or axis located substantially at the meeting point of the edges of the wipers at the end of the toe. For imparting the closing movements to the wipers the wiper holders 22 are provided with rack teeth 30 in engagement with pinions 32 which are operated by a double rack member 34 connected by a pin 36 to a wiper-closing sleeve 38 guided in the sleeve 26.

The wiper-closing sleeve 38 is operated yieldingly by a plunger 40 slidably mounted in a bushing 42 and in a cylindrical recess 44 in the sleeve 38, the plunger being arranged to impart forward movement to the sleeve through a comparatively stiff spring 46 which engages at one end a shoulder on the plunger and at the other end an adjustable bushing 48 which is threaded in the sleeve 38. The bushing 48 is splined on the plunger 40, so that by turning the plunger, as by use of a knurled head 50, the bushing is adjusted to change as desired the compression of the spring 46. The wipers are thus permitted to yield, for example, in upwiping the toe. To limit the extent to which they may yield, in order to provide for adequate overwiping pressure, lock nuts 52 on the plunger 40 are arranged to engage the bushing 42.

The plunger 40 is operated by a hand lever 54 pivoted at 56 on the head 10, the lever being connected by a link 58 to a nut 60 (Fig. 2) which is threaded on a sleeve 62 mounted on the plunger 40 between the head 50 and a fixed washer 64. The threaded sleeve 62 may thus be utilized to adjust the plunger 40 to swing the wipers about their center without advancing them, and thereby to determine their proper starting position, the sleeve being held normally from turning by means of a friction member 66 (Fig. 1).

The hand lever 54 is utilized to advance the wipers lengthwise of the shoe as well as to

close them, and for this purpose it is connected by a link 68, pivoted at 70 on an extension of the lever, to a lever 72 which is pivoted at 74 on the head 10 and is connected in turn to the wiper-advancing sleeve 26. The connections between the lever 72 and the sleeve 26 comprise a block 76 secured to the sleeve 26 and guided in a slot 78 in the head 10, this block having thereon a pin 80 which carries a bearing block 82 slidably mounted in a slot in the end of the lever 72. It will be evident that as the hand lever 54 is operated to advance the plunger 40 and thus to impart swinging movements to the wipers to close them laterally of the toe, it also serves through the connections described to impart to the sleeve 26 wiper-advancing movement the extent of which bears a predetermined relation to the extent of the closing movement of the wipers.

It is usually desired, particularly on welt work, to wipe the upper inwardly for the same distance from the edge of the shoe bottom at the sides of the toe as at the end of the toe. To accomplish this result in the best manner a different extent of angular swinging movement of the wipers, for the same extent of bodily advancing movement, is required for toes of materially different shapes, for example, for pointed toes as compared with blunt toes. It is accordingly desirable to vary relatively the rates of the advancing and closing movements of the wipers, and the machine herein shown is provided with means whereby such a variation may be conveniently effected. To this end, there is provided means for adjusting the link 68 lengthwise of the lever 72 to change the effective length of this lever. It will be seen by reference to Fig. 1 that the link 68 is connected by a pivot pin 83 to a block 84 slidably mounted in a curved slot 86 in the lever 72. On the head of the pin 83 is a slide 87 (Fig. 3) mounted in a guideway extending transversely of a block 88 which is mounted on an adjusting screw 90 swivelled in bearing members 92 on the lever 72. By turning the screw 90 the link 68 may thus be swung about its pivot 70 and its point of connection to the lever 72 adjusted lengthwise of the lever. It is desirable that such an adjustment be made without affecting the position of the wipers relatively to the shoe at the critical point in the lasting operation, that is, when the wipers are closed about the toe in position to begin their overwiping movements, and accordingly the construction is so designed that with the wipers in this position the center of curvature of the slot 86 in the lever 72 coincides with the pivotal axis 70 of the link 68. It will be evident that this adjusting means may be utilized not only to set the parts for wiping the upper inwardly to the same distance all around the toe, but also for wiping it farther inwardly, for example, at the sides

than at the end of the toe, as may be desired on some kinds of shoes.

It will thus be seen that there are provided separate connections between the hand lever 54 and the wipers for advancing and retracting the wipers bodily lengthwise of the shoe and for swinging them toward or from each other. It will be understood that in operation the plunger 40 and the sleeve 38 must not only move forwardly with the wiper-advancing sleeve 26, but must move faster than the sleeve 26 in order to effect the closing movement of the wipers, the lever 72 being so constructed and arranged relatively to other parts as to provide for such relative movement between the wiper-advancing and wiper-closing connections. It will also be seen that the relation between the rate of the advancing movement of the wipers and the rate of their closing movement, and consequently the relation between the extents of these different movements, may be readily varied by adjusting the screw 90 to change the effective length of the longer arm of the lever 72.

In the operation of the wipers it is intended that the spring 46 in the wiper-closing connections shall yield as the wipers are closed about the toe preparatory to the upwiping operation, so as to insure that during the upwiping operation the wipers will bear with effective pressure on the sides of the toe while they are held by the wiper-advancing connections against the end of the toe. In the operation of wiping the upper inwardly over the feather of the insole of a welt shoe the spring 46 will yield until one of the nuts 52 engages the bushing 42, so that the final application of the overwiping pressure against the rib of the insole will be positive at the sides of the toe as well as at the end of the toe. By turning the plunger 40 the tension of the spring 46 may be readily varied without affecting the position of the wipers; and by turning the sleeve 62 the plunger 40 may be adjusted lengthwise to swing the wipers about the axis of their closing movement and thus to adjust them for shoes of different widths without affecting the connections whereby they are advanced lengthwise of the shoe and without affecting the tension of the spring 46.

While the invention is herein illustrated in its application to a machine in which the various movements are effected manually, it will be understood that in various novel aspects the invention is likewise applicable to power-operated machines.

Having described my invention, what I claim as new and desire to secure by Letters Patent of the United States is:—

1. In a lasting machine, the combination with shoe-positioning means, of end-embracing wipers, a hand lever, and separate connections between said lever and the wipers for

advancing and closing the wipers respectively.

2. In a lasting machine, the combination with shoe-positioning means, of end-embracing wipers, members for imparting to said wipers advancing and closing movements respectively, a hand lever, an operating connection between said hand lever and one of said members, a second lever connected to the other of said members, and an operating connection between the hand lever and said second lever. 70 75

3. In a lasting machine, the combination with shoe-positioning means, of end-embracing wipers, a wiper head for supporting said wipers, a sleeve in the wiper head for advancing the wipers, a plunger in said sleeve for imparting closing movement to the wipers, a hand lever connected to said plunger, a second lever pivoted on the wiper head and connected to said sleeve, and an operating connection between said second lever and the hand lever. 80 85

4. In a lasting machine, the combination with shoe-positioning means, of end-embracing wipers, a plunger and a sleeve about the plunger for closing and advancing the wipers respectively, and a hand lever separately connected to said sleeve and plunger. 90

5. In a lasting machine, the combination with shoe-positioning means, of end-embracing wipers, a hand lever yieldingly connected to said wipers for closing them, and separate connections between said hand lever and the wipers for imparting to them positively advancing movement. 95 100

6. In a lasting machine, the combination with shoe-positioning means, of end-embracing wipers, a hand lever, and separate connections operated by said hand lever for imparting to the wipers advancing and closing movements respectively, one of said connections including a member yieldable in response to pressure of the wipers against the shoe and having means for limiting its yield. 105 110

7. In a lasting machine, the combination with shoe-positioning means, of end-embracing wipers, a hand lever, and separate connections between said hand lever and the wipers for advancing and closing the wipers respectively including means for adjusting the wipers in the direction of their closing movement without advancing them. 115

8. In a lasting machine, the combination with shoe-positioning means, of end-embracing wipers, a hand lever, connections between said hand lever and the wipers for imparting to the wipers advancing and closing movements, and means for adjusting said connections to vary relatively the rates of 120 125 said movements.

9. In a lasting machine, the combination with shoe-positioning means, of end-embracing wipers, a hand lever, and separate trains of mechanism operated by said hand lever for 130

imparting to the wipers advancing and closing movements respectively, one of said trains of mechanism comprising a second lever with provision for varying its effective length to vary relatively the rates of advancing and closing movement of the wipers.

10. In a lasting machine, the combination with shoe-positioning means, of end-embracing wipers, a hand lever, separate trains of mechanism operated by said hand lever for imparting to the wipers advancing and closing movements respectively, one of said trains of mechanism comprising a second lever and a link connecting it to said hand lever, and means for adjusting said link relatively to the second lever to vary the effective length of said lever.

11. In a lasting machine, the combination with shoe-positioning means, of end-embracing wipers, and operating means for imparting to said wipers advancing and closing movements, said operating means being adjustable to vary relatively the rates of said advancing and closing movements of the wipers without affecting the relation of the edges of the wipers to the shoe at the point where said edges begin to wipe the upper inwardly over the shoe bottom.

12. In a lasting machine, the combination with shoe-positioning means, of end-embracing wipers, and operating means for imparting to said wipers advancing and closing movements in predetermined relation, said operating means comprising parts relatively adjustable to vary relatively the rates of the advancing and closing movements of the wipers including a member pivoted for adjustment about an axis in such relation to other parts as not to affect the relation of the wipers to the shoe at the point where the wipers begin to wipe the upper inwardly over the edge of the shoe bottom.

13. In a lasting machine the combination with shoe-positioning means, of end-embracing wipers, a hand lever, and separate trains of mechanism between said hand lever and the wipers for advancing and closing the wipers respectively, one of said trains of mechanism comprising parts relatively adjustable to vary relatively the rates of the advancing and closing movements of the wipers and constructed to effect such change of rate without altering the relation of the wipers to the shoe at the point where the wipers begin to wipe the upper inwardly over the edge of the shoe bottom.

14. In a lasting machine, the combination with shoe-positioning means, of end-embracing wipers, a hand lever, separate trains of mechanism operated by said hand lever for imparting to the wipers advancing and closing movements respectively, one of said trains of mechanism comprising a second lever and a link connecting it to the hand lever, the connection between said second lever and link being adjustable in an arc the center of which

coincides with the pivotal connection of the link to the hand lever when the wipers are substantially at the point where they begin to wipe the upper inwardly over the edge of the shoe bottom.

15. In a lasting machine, the combination with shoe-positioning means, of end-embracing wipers, and means for effecting advancing and closing movements of said wipers comprising a lever for effecting both of said movements, a second lever arranged to be utilized in effecting one of said movements and an operating connection between said levers.

16. In a lasting machine, the combination with shoe-positioning means, of end-embracing wipers, and means for effecting advancing and closing movements of said wipers comprising a lever for effecting both of said movements, a second lever arranged to be operated by the first lever to effect one of said movements, and means for relatively varying the effective lengths of said levers to change the relation between the rates of the advancing and closing movements of the wipers.

17. In a lasting machine, the combination with shoe-positioning means, of end-embracing wipers, and wiper-operating means comprising members movable lengthwise of the shoe for advancing and closing the wipers respectively, an operating lever, and separate operating connections between said lever and the different members.

18. In a lasting machine, the combination with shoe-positioning means, of end-embracing wipers, an operating lever, and separate connections between said lever and the wipers for advancing and closing the wipers respectively, one of said connections being positive and the other yielding in its action on the wipers.

19. In a lasting machine, the combination with shoe-positioning means, of end-embracing wipers, an operating lever, and separate connections between said lever and the wipers for advancing and closing the wipers respectively, one of said connections being positive and the other yielding in its action on the wipers, and means for rendering said other connection positive in the final application of the wiper pressure.

20. In a lasting machine, the combination with shoe-positioning means, of end-embracing wipers, and means for imparting closing movement to said wipers including spring means arranged to transmit movement to the wipers and to yield in response to resistance of the shoe, and members arranged for positive engagement with each other to limit said yield while said spring means continues its action on the wipers.

21. In a lasting machine shoe holding means and wiping mechanism, the latter comprising wiper plates movable as a whole toward and from the shoe and simultaneously swingable toward and from each other, and

connections for actuating said plates comprising a carriage supporting the wiper plates, an operating member or handle, a connection from the handle to the carriage, and a connection from the handle to the wiper plates adapted to effect their swinging movements.

22. A lasting machine as in claim 21 and wherein the operating lever has slow actuating connections to the carriage, and faster moving connections to the wiper plates.

23. A lasting machine as in claim 21 and wherein the operating member has actuating connections to the carriage and other connections to the wiper plates, and means for initially adjusting one of such connections to set the plates toward or from each other according to the shape or size of the shoe. 15

In testimony whereof I have signed my name to this specification.

ARTHUR F. PYM.
